Fig. 1.

Fig. 2.

A line drawing of a ciliophore, showing a large, roughly rectangular body with a prominent, roughly circular nucleus situated near the center. A smaller, roughly circular structure, likely a contractile vacuole, is located to the right of the nucleus. The body is bounded by a wavy line representing the cell membrane. The number '5' is written near the nucleus, and the number '28' is written near the right side of the body.

UNITED STATES PATENT OFFICE.

STANLEY STANCZYK, OF LYNN, MASSACHUSETTS.

TORCH.

Application filed June 6, 1927. Serial No. 196,930.

My invention relates to torches and particularly to automatic hand torches using alcohol, gasoline, or other suitable hydrocarbon fluid and which are employed, for example, in carrying out soldering operations and the like. The object of my invention is to improve the construction and mode of operation of torches of the kind indicated.

Alcohol and gasoline torches of the class referred to include a burner having a wick that is lighted and a vapor delivering nozzle, the wick being supplied with alcohol or gasoline from one reservoir and the vapor delivering tube also containing a wick that is supplied with alcohol or gasoline from another reservoir. In operating a torch of this kind the burner wick is lighted and its flame heats the vapor delivering nozzle and vaporizes the gasoline that is delivered to the latter by its wick causing vapor to be discharged from the nozzle under pressure across and through the flame from the burner thus projecting a concentrated pencil-like flame. In all forms of torches, as heretofore constructed, and with which I am familiar, the vapor delivering nozzle was constituted by the end of a tube containing the wick referred to and continued use of a torch so constructed resulted in so overheating the tube as to frequently char and thereby destroy the wick within the tube requiring the device to be disassembled and a new wick substituted for the destroyed one. My invention provides an improved torch wherein the delivery end of the tube or conduit supplying the gasoline that is to be vaporized is surrounded by a jacket that provides an annular chamber or space between the jacket and the delivery end portion of the tube through which the alcohol or alcohol vapor passes in a re-entrant fashion to an outlet port some distance back of the delivery end of the tube, said outlet being positioned to project the vapor discharging therefrom in a stream across or through the flame of the burner. This construction results in several important advantages, viz., the jacket being interposed between the end portion of the delivery tube and the flame of the burner with an intervening annular space occupied by vapor that is traveling toward the outlet effectually insulates the end portion of the delivery tube sufficiently to prevent charring of the wick within said tube no matter how long the torch is used; the jacket provides a retort of relatively large capacity within which is maintained a supply of vapor under

pressure, and by properly positioning the out-let from this retort with respect to the burner, particularly as described later, the torch will function the same when held in any possible position. So far as I know no torch of this class has heretofore been produced which will function in all possible positions in which it may be held.

Other features of my invention are hereinafter pointed out.

In the accompanying drawings:

Figure 1 is a side elevation of a torch constructed in accordance with my invention.

Figure 2 is a central vertical sectional view of the torch shown in Fig. 1.

Figure 3 is a section on line 3—3 of Fig. 1.

Figure 4 is an enlarged sectional view on line 4—4 of Fig. 2.

My improved torch as herein shown comprises a hollow sheet metal body 1 constructed interiorly, and intermediate its ends, with a partition 2 providing two reservoirs 3 and 4. Within the body 1 is a burner tube 5 whose lower end terminates short of but near the bottom wall 6 of the body and whose upper end portion extends through and is soldered or brazed to the top wall 8 of the body. The body 1 is, as shown in Fig. 3, of flattened tubular form and near one end of top wall 8 there is provided a hole 9 within which is soldered or brazed an exteriorly threaded nipple 10 which projects outwardly beyond the end wall 8. A delivery tube 11 extends through the nipple 10 whose outer end portion is formed with a counterbore 12 providing a shoulder 13 serving as a seat for a fiber washer 14. Against the outer side of the fiber washer 14 is seated an annular flange 15 provided on the delivery tube 11. An interiorly threaded cap 16 is screwed down on to the nipple 10 and by engagement with the flange 15 clamps the latter tightly against the fiber washer 14, and the latter tightly against the shoulder 13 thereby providing a tight joint past which it is impossible for the contents of the reservoir 4 to leak. At the same time the delivery tube 11, as will be clear, can be turned on the axis of the nipple 10 to swing its delivery end laterally. That is, the outer portion of the delivery tube 11 is of goose-neck form and its delivery end portion 11^a can be swung laterally on the axis of the nipple 10.

The upper end portion of the burner tube 11 extends outside of the end wall 8 and terminates near the delivery end portion 11^a.

of the delivery tube 11. This burner tube 5 is obliquely disposed with relation to the body 1 so that its inner end is near one side of said body while its opposite end portion is 5 near the opposite side of said body and the outer extremity of this burner tube is finished off so that its chime 18 occupies a plane that is parallel, or approximately parallel, with the axis of the delivery end portion 11^a of the delivery tube 11. Within the burner tube 5, and filling the interior thereof, is a wick 17. Inasmuch as the burner tube 5 is obliquely disposed with relation to the body 1 and the axis of the delivery portion 11^a of the delivery tube 11, and its chime 18 occupies a plane that is parallel with the axis of the latter, said chime is oblique with relation to the axis of the burner tube 5 and, therefore, of elliptical form as shown in Fig. 3, the width 20 of said ellipse being the same as the diameter of the tube 5 but with the length of the ellipse greater than said diameter. Therefore, the surface area of the exposed wick at the chime 18 is greater than the cross-sectional area of 25 the tube 5. In other torches, as heretofore constructed, the chime 18 has always been at right angles to the axis of the tube 5 and consequently the area of the exposed wick was the same as the cross-sectional area of the 30 tube 5 and as a result flooding would occur at the chime 15 causing the overflow of burning fuel. By making the chime 18 oblique with relation to the axis of the tube 5 the exposed area of the wick at the delivery end of 35 the tube 5 is greater than the cross-sectional area of said tube so that the rate of combustion for a given size tube 5 is greater than heretofore and sufficiently great to effectually prevent flooding. By positioning the burner tube 5 obliquely, as shown and described, it 40 will be clear that if the torch is turned from the position shown in Fig. 2 ninety degrees in a left hand or contra-clockwise direction the inner end of the burner tube 5 will then be at the top of the reservoir 3 and its liquid 45 contents at the bottom, thus preventing a head which would force the liquid down through the wick 17 faster than it was being consumed at the chime 18. It will also be clear that if the torch is turned ninety degrees in a clockwise, or right hand, direction from the position shown in Fig. 2, the delivery end of the burner tube 5 will be very 50 slightly below, or above the level of the liquid within the reservoir 3 so that there will then be practically no head to force the liquid through the wick to the delivery end. It will also be clear that if the torch is turned upside down from the position shown in Fig. 2 the 55 inner end of the burner tube 5 will be closely adjacent or above the level of the liquid within reservoir 3 so that in this position also, there will be no head of liquid to speak of to force the same through the wick to the 60 delivery end of tube 5. It should be clear, 65

therefore, that however the torch may be positioned there is, as a practical matter, no time when there is any substantial head of liquid within reservoir 3 tending to force liquid out through the wick of burner tube 5. 70

The laterally extending delivery portion 11^a of the delivery tube 11 is provided with an exteriorly threaded flange 19 to receive upon it the interiorly threaded inner end of a retort or jacket in the form, as herein shown, 75 of a sleeve 20 that is closed at its outer end by an end wall 21.

In the end of the delivery tube 11 is provided a screen 22 herein shown as a strip of wire gauge or fabric rolled into cylindrical 80 form and pushed into the end of the tube so that it holds itself in place frictionally.

Within the delivery tube 11 there is provided the usual wick 23 within whose inner end portion is incorporated a metal wire 24 85 for use in threading the wick through the hole 25 of bushing 10 when assembling the parts. This wick fills tube 11 up to screen 22 and its opposite end extends to the bottom of reservoir 4. 90

A cap 26 connected with delivery tube 11 by a chain 27 is provided for application to the outer end of burner tube 5 when the torch is not in use and when in position upon said tube it is prevented from accidental displacement by positioning the delivery tube 11 immediately above the same. When the torch is to be used the delivery tube is swung aside and the cap removed after which the delivery tube is returned to its position opposite the end of burner tube 5. A pair of spring jaws 28 are provided upon the side of body 1 with which chain 27 may be engaged when the cap is removed from the 100 burner tube. 105

When the torch is in operation the flame from the upper end of the burner tube 5 heats the retort sleeve 20 and warms the upper end of the delivery tube 11 thereby vaporizing the alcohol or gasoline that is within the tube 11 and sleeve 20, the fluid passing up through the wick 23 and screen 22 into the retort sleeve 20 where it is thoroughly vaporized. From the forward end of the retort sleeve 20 the vapor passes backwardly through the annular space between the nozzle portion 11^a of tube 11 and the retort sleeve 20 into a relatively large annular chamber 29 from which it escapes under pressure through the outlet 30 that is directed forwardly across and through the flame from burner tube 5. As will be seen from Fig. 2 the outlet 30 is positioned above the middle of the outlet end of the burner tube 5 and close to the same. The result is that the flame is so confined between the retort sleeve 20 and the outlet end of burner tube 5 that no matter in what position the torch is held the outlet 30 is within the flame from the burner tube and, therefore, the torch operates the same no matter what 115 120 125 130

position it occupies. This is due also in part to the fact that the stream of vapor issuing under pressure from the outlet 30 creates a suction or draft which holds the flame of the burner tube 5 around said stream whatever be the position of the torch and I find that this effect is best secured by positioning the outlet 30 close to and opposite the middle of the outlet end of the burner tube.

10 The reservoir 3 is provided with a filler hole 31 normally closed by a removable cover 32. Reservoir 4 is filled through the nipple 10 after removing tube 11 and cap 16.

What I claim is:

15 1. A torch of the character described having in combination two separate reservoirs; a burner tube leading from one of said reservoirs; a wick within said burner tube; a delivery tube leading from the other reservoir 20 having its delivery end portion opposite and crosswise of the end of said burner tube; a wick within said delivery tube; a retort surrounding the delivery end portion of the delivery tube whose wall is interposed between the burner tube and said delivery end portion, 25 and a vapor outlet for said retort adjacent the

rear end of the latter positioned in spaced relation to said burner tube wick and approximately opposite the middle thereof.

2. A torch of the character described constructed in accordance with claim 1 and wherein the axis of the burner tube is disposed obliquely with relation to the axis of the delivery portion of the delivery tube and with the chime of said burner tube in a plane 30 oblique with relation to the axis of the burner tube and parallel with the axis of the delivery portion of the delivery tube.

3. A torch of the character described comprising a fuel container, a delivery tube 40 leading from said container having a straight normally horizontal delivery end portion, a retort jacket surrounding the delivery end portion of said tube in spaced relation thereto, said jacket having an outlet orifice, and a 45 burner tube connected with said container and having its delivery end disposed immediately below said retort jacket intermediate the ends of the latter.

Signed by me at Boston, county of Suffolk 50 and State of Massachusetts, May, 1927.

STANLEY STANCZYK.
